To all whom it may concern:

Be it known that I, ARTHUR L. HALLIDAY, of Yonkers, in the county of Westchester and State of New York, have invented and produced a new and original Design for a Carpet, of which the following is a full description, in connection with the accompanying photograph, which represents a face view of my new design for a carpet.

10 This invention relates to a new configuration of ornaments that decorate the face of a carpet or analogous fabric.

The photograph shows the body of the carpet to be composed of several stripes, which 15 are marked *a b d e f g h i*. The stripe *b* consists of groups *C* & *f* of rosettes, between which are figures *D*, that are composed 20 of vertical lines and dots, as shown. The stripe *d* carries representations of leaves *E*, rosettes *F*, and fanciful figures *G* and *H*. There is also

a group, *I*, of diamond-shaped figures in the lower part of the stripe *d*. The stripe *e* is composed of oval figures placed in a row. The 25 broadest stripe *f* contains a cluster of geometrical figures, *J*, and an oval rosette, *K*, with which are connected smaller rosettes *j* and *l*, and a fanciful figure, *L*. The stripe *g* is composed of diamond-shaped figures and dots, as 30 indicated.
